United States Patent Office

Des. 184,458
Patented Feb. 17, 1959

184,458

HEATER CASING

Jean O. Reinecke, Oak Park, Ill., assignor to Modine
Manufacturing Company, Racine, Wis., a corporation
of Wisconsin

Application November 16, 1956, Serial No. 43,799

Term of patent 14 years

(Cl. D81—19)

Fig. 1 is a perspective view of a heater casing showing my new design;

Fig. 2 is a front elevational view on a slightly reduced scale; and

Fig. 3 is a similarly scaled side elevational view.

I claim:

The ornamental design for a heater casing, as shown.
